R. L. Benson
ATTORNEY.

UNITED STATES PATENT OFFICE

2,246,713

KNITTING REEL

Albert L. Benson, Los Angeles, Calif.

Application July 15, 1940, Serial No. 345,521

1 Claim. (Cl. 242—130)

This invention relates to a reel, more particularly intended for rotatably supporting a skein from which thread is being withdrawn for knitting, but also capable of being used to advantage wherever a ball of twine or yarn is required to be supported to be unwound as it is used.

Among the objects of the invention are:

To provide a superior means for rotatably supporting a ball of crochet thread which has been sold to the user wound on a core mountable on a bobbin shaft, but the skein purchased, if necessary, can be mounted directly on the bobbin shaft provided by the invention; to provide an improved automatic feed for unwinding thread and yarn as it is used in crocheting and knitting; to provide a more freely rotatable bobbin which automatically centers itself on the bobbin shaft, and to provide, in conjunction with the aforesaid valuable features, means to safely guard against the flexible connection, while being unwound, becoming in any way entangled or obstructed from being freely fed for use.

A more specific object of the invention is to provide an improved combined bobbin base and bobbin shaft, which is rotatably mounted in an overlying relation to a supporting base, and which is provided with a skirt portion which forms a superior guard to prevent the yarn or string being unwound from becoming obstructed as it is fed from the device.

Another specific object of the invention is to provide an improved combination between a tubular bobbin shaft and supporting spindle therefor, said bobbin shaft being constructed to automatically center itself upon said spindle in a freely rotatable manner.

Other objects, advantages, and features of invention will hereinafter appear.

Referring to the accompanying drawing which illustrates what is at present deemed to be a preferred embodiment of the invention,

Fig. 1 is a perspective view of the device showing a skein of yarn supported thereon.

Fig. 2 is a perspective view of the device showing a ball of twine or thread wound upon a tubular core member, said core member being telescoped over the bobbin shaft of the device.

Fig. 3 is a view partly in perspective and partly in vertical mid-section, the device being shown per se, without any ball of twine or the like being supported thereby.

Referring in detail to the drawing, in Fig. 3 the device is shown comprising a circular spindle base 5 having a substantially flat top surface 6. Said base may be made solid, but by preference

is either cored out at its under side or is shaped, as shown, as a circular plate having a depending flange or peripheral wall 7. A spindle 8 upstands from said base, the lower end portion of said spindle being securely fixed to the base in any preferred manner. The upper end of said spindle 8 is tapered at 9 as shown.

A tubular bobbin shaft 10 loosely surrounds said spindle, said shaft having a closed upper end portion 11 whereby it is rotatably supported upon the top of said spindle. Said upper end portion 11 presents interiorly a conical surface thus causing the tubular shaft to center itself upon, and provide an antifriction bearing for, the spindle as shown in Fig. 3. Said bobbin shaft 10 is fixed at its lower end to the central part of the horizontal top portion 12 of the bobbin base 13. The length of the tubular shaft 10 is so proportioned with respect to that of the spindle 8 that the plate 12 is rotatably supported slightly above the top of the supporting base 5, as well shown in Fig. 3. The central portion of said plate 12 is provided with an aperture 14 through which the spindle 8 extends with a working fit.

The central apertured portion 14 of the bobbin plate 12 affords what is at present deemed to be the best means for providing a lower bearing or guide for the spindle 8, but if desired other suitable bearing means in a downwardly spaced relation to the top of the spindle 8 may be provided.

The bobbin base 13 is furnished with a skirt portion which comprises a dependent peripheral flange 15, said flange being in an outwardly spaced relation to the peripheral wall 7 of the supporting base 5. The lower edge portion of said flange 15 is provided with an outwardly directed flange, bead or curl 16. As well shown in Fig. 3, said part 16 is maintained in an upwardly spaced relation to the lower side of the base 5 and hence does not interfere with the free rotation of the bobbin shaft when said base 5 is resting upon a flat supporting surface. At the same time, said part 16 provides an additional safeguard against the thread or other flexible connection from becoming looped under the flange 15 while it is being unwound from the reel.

In Fig. 1 a skein of yarn 20 is shown mounted upon the device, and in Fig. 2 a twine ball 21 is shown mounted thereon, said ball having a central core 22 which is sold with the twine and which can be telescoped over the tubular shaft 10.

Whether a skein of yarn or ball of twine be mounted upon the device, in either case free and satisfactory unwinding is assured.

It should be understood that the present dis-

closure is for the purpose of illustration only and that this invention includes all modifications and equivalents which fall within the scope of the subject matter claimed.

What I claim is:

In a reel, a circular spindle base having a substantially flat top surface provided with a depending flange, a spindle having a tapered upper end upstanding from the central portion of said base, a tubular bobbin shaft loosely surrounding said spindle, said bobbin shaft having a closed upper end with a conical under surface which rests rotatably upon the tapered top of said

spindle, and a horizontally disposed circular base plate supported by said bobbin shaft in an upwardly spaced relation to said spindle base, said base plate having a depending skirt portion completely enveloping said spindle base in an outwardly spaced relation thereto, said base plate extending inwardly of the mouth of said tubular shaft to form a cross wall which is provided with a central bearing and guide aperture where-through said spindle extends with a working fit, said aperture being located concentric of said tubular shaft.

ALBERT L. BENSON.
